UNITED STATES PATENT OFFICE

159,707

TOY DOG

Jay V. Zimmerman, Clayton, Mo.

Application April 10, 1950, Serial No. 9,114

Term of patent 14 years

(Cl. D34—2)

To all whom it may concern:

Be it known that I, Jay V. Zimmerman, a citizen of the United States, residing at the city of Clayton, county of St. Louis, State of Missouri, have invented a new, original, and ornamental Design for a Toy Dog, of which the following is a specification, reference being made to the accompanying drawing, forming a part thereof, in which

I claim:

The ornamental design for a toy dog, substantially as shown.

JAY V. ZIMMERMAN.
